(57) **CLAIM**

The ornamental design for an extender for a Z-bar assembly on a door frame, as shown and described.

DESCRIPTION

FIG. 1 is a front perspective view of an extender for a Z-bar assembly on a door frame according to the invention;

FIG. 2 is a front elevation view of the extender for a Z-bar assembly on a door frame depicted in FIG. 1;

FIG. 3 is a side elevation view of the extender for a Z-bar assembly on a door frame depicted in FIG. 1;

FIG. 4 is an opposing side elevation view of the extender for a Z-bar assembly on a door frame depicted in FIG. 1;

FIG. 5 is a rear elevation view of the extender for a Z-bar assembly on a door frame depicted in FIG. 1.

FIG. 6 is a top plan view of the extender for a Z-bar assembly on a door frame depicted in FIG. 1;

FIG. 7 is a bottom plan view of the extender for a Z-bar assembly on a door frame depicted in FIG. 1; and,

FIG. 8 is a rear perspective view of the extender for a Z-bar assembly on a door frame according to the invention.

The broken-line disclosure in the views is for illustrative purposes only and forms no part of the claimed design.
